PUMP PRIMING SYSTEM

Allan G. Sheppard, Elmira, N. Y., assignor to
American-La France-Foamite Corporation, Elmira, N. Y., a corporation of New York

Application March 2, 1942, Serial No. 433,089

7 Claims. (Cl. 103—113)

The invention is an improved priming system for centrifugal pumps such as used in motorized fire engines and wherein precautions are necessary for preventing passage of water from the pump to the suction mechanism by which the priming is effected. When the source of suction is a combustion engine, as customarily the case, or other mechanism normally intended to handle gases only, disastrous results may ensue from the entry of water into it. Such entry may occur through inadvertence as by connecting the pump's intake to a source of water under pressure such as a hydrant, or to another fire engine, without first closing the priming connection, in which case the hydrant pressure may flood the engine through the priming line. Prevention of accident from this cause is highly important and is effectively afforded by the present invention without any mechanical complication.

In the accompanying drawing, Fig. 1 shows the organization of the invention in a conventional type of fire engine, parts only of which appear, and Fig. 2 is a larger scale diagram of the priming line connections.

The centrifugal pump indicated generally at 1 is shown as mounted on the chassis 2 of the fire engine and may be understood to have two or more discharge outlets 3 controlled by gates 4 and two suction intakes 5, one on each side of the vehicle, also the usual control appurtenances which are omitted from the figure. One or the other of these intakes is intended to be connected to a source of water supply, which may be in some cases a hydrant or another fire engine, and in others a free body of water at a lower level, such as a river, pond, etc., in which latter case priming the pump is necessary. By the application of suction to the pump casing the water is drawn up into it through the connected intake, the other intake and the discharge gates of course being closed.

The combustion engine is shown in outline at 6, and may be the same engine that propels the vehicle and drives the pump, being understood to have the appropriate clutches for this purpose as customary in motor pumper. Its exhaust pipe is indicated at 7 in the usual location and the energy of the gas flow therein is utilized for creating the priming suction. This is done by closing a deflector valve 8 in the exhaust pipe 7 thereby diverting some or all of the gas into an ejector 9 discharging to atmosphere. The throat part of this ejector, which is the immediate source of suction, is connected by a pipe or conduit system to some upper part of the pump casing, pref-

erably at the spot marked 10 in Fig. 1. The ejector assembly can be and is shown as clamped directly on the exhaust pipe, being preferably directed downwards, although it can be located wherever convenient. In an ordinary case a jet of about $\frac{3}{8}$ " diameter will do efficient work.

The priming line between the gas ejector 9 and the pump includes a T-fitting 11 which is preferably another or second ejector and herein for distinction called a water ejector. Its entry or nozzle end, marked 12, is connected through manual valve 13 and elbow 14 with the top 10 of the pump intake and its exit or recovery end 15 leads through a lightly-loaded, swing-type check valve 16 to an escape outlet 17, discharging to ground, while its intermediate or throat section 18 is connected by pipe 19 and check valve 20 with the throat section 21 of the gas ejector 9.

The escape check valve 16 being normally closed, suction created by the gas ejector is transmitted through the parts just described to the pump, provided the priming valve 13 is opened, and thereby water can be sucked into the pump, thus priming it, when that is required. Discharge of water from the gas ejector is the indication that the pump is primed.

The valve 13 is provided with a control handle at the operator's station as indicated at 22 and is supposed to be closed when the pump has been primed. If however this valve is open and the pump receives water, not by suction but by the pressure of a hydrant for example, the velocity of its flow from the pump through the fitting 11 will carry it out through the easily opened swing check 16 discharging to ground. It will thereby be kept from entering and choking the exhaust gas ejector 9 which might result in stalling the engine and in the flow of water through the exhaust pipe into the engine cylinders.

40 The capacity of the check-valved escape 16 is large enough so that little or no water enters the suction-producing gas ejector 9 under such circumstances, and this effect is made certain by constituting the fitting 11 as a water ejector with 45 its jet nozzle 18 appropriately restricted. It is possible to restrict this nozzle to such degree that the jet velocity will be high enough to open the escape passage 16 under any water flow large enough to choke the gas ejector if admitted to 50 the latter, which is to say, that if the jet velocity is not sufficient to open the escape the volume of water then passing the nozzle will not be of such magnitude as to stop the action of the gas ejector if it should arrive in the latter by way of the line 55 19. In an ordinary case the nozzle 18 would

have a circular diameter of about $\frac{1}{2}$ inch which is ample to transmit the suction effect when priming. The pipe 19 is shown connected to the top side of the water ejector but it can be connected to either side or the bottom as desired and if connected to the bottom will provide quicker drainage for water when the use of the priming line has been discontinued. The check valve 20 in this line closes whenever the pressure at the pump-connected end drops below that at the throat 21, which is possible to occur if for any reason the engine should slow down during the priming and it thus serves to hold the priming suction at such times. The fitting or water ejector 11 with its escape outlet can obviously be connected at any point desired in a priming line to afford certain and fool-proof protection against injury or malfunctioning of the suction mechanism. The priming line can be left open if desired, to be closed only on such occasions as when water in the suction side of the pump is under pressure, for preventing wastage through the pipe 17 at such times, particular care about closing the valve 13 being no longer necessary.

I claim:

1. In a pump priming system having a pump and a suction source for priming the pump and a priming line for transmitting suction from the source to the pump including a water ejector having its entry connected with the pump, its recovery with an escape outlet and its throat with said source, and means for preventing inward flow through said outlet.

2. In a pump priming system having a pump and a combustion engine connected to drive the pump and provided with an exhaust-gas ejector constituting a suction source, and a priming line for transmitting suction from said source to the pump for priming the latter including a water jet ejector having its entry connected with the pump, its water-jet discharging into an escape outlet and its throat section connected with said suction source, and means for preventing inward flow through said outlet.

3. In a pump priming system having a pump and a combustion engine connected to drive the pump and provided with a gas ejector as a suction source, and a priming line for transmitting suc-

tion from said source to the pump for priming the latter including a water ejector having its entry connected with the pump, its recovery with an escape outlet and its throat section with the throat section of said gas ejector.

4. In a pump priming system for fire engines, the combination with a pump and a pump-driving combustion engine provided with an exhaust-gas ejector in its exhaust line as a suction source, a priming line for transmitting suction from said source to the pump for priming the latter including a fitting having its entry connected with the pump, its other end with an escape outlet and its intermediate section with the throat section of said gas ejector.

5. In a pump priming system having a pump and a combustion engine provided with an exhaust-gas ejector in its exhaust line constituting a suction source, a priming line for transmitting suction from said source to the pump for priming the latter including a fitting having its entrance end connected with the pump, its exit end connected with an escape outlet and having a conduit connecting its intermediate section with said suction source, and means for preventing inward flow through said conduit and said escape outlet.

6. In a pump priming system for fire engines, the combination with a pump and a pump-driving combustion engine, an exhaust-gas ejector in its exhaust line and operable thereby, a priming line for transmitting suction from said gas ejector to the pump for priming the latter including a water-jet ejector having the entry to its jet nozzle connected with the pump, its exit connected with an escape outlet and its throat section with said gas ejector, and a check-valve for preventing inward flow through said outlet adapted to open under the force of the jet from said nozzle, the diameter of said nozzle being predetermined not to overload the gas ejector when the jet force is incapable of opening said check-valve.

7. In a pump priming system, a pump, an exhaust gas ejector constituting the source of suction, a priming line connecting the latter to the pump, an ejector fitting in such line for discharging water from the pump and a check valve in such line closing toward the pump.

ALLAN G. SHEPPARD.
